United States Patent Office

Des. 221,811
Patented Sept. 7, 1971

221,811

CANDLE

Wilfred L. Reiher, Sun City, Ariz., assignor to Candle World

Filed Sept. 23, 1968, Ser. No. 13,667

Term of patent 14 years

Int. Cl. D26—05

U.S. Cl. D73—1

The figure on the drawing is a perspective view of a candle showing my new design. The details and features seen in this view continue around the candle.

I claim:

The ornamental design for a candle, as shown and described.
